UNITED STATES PATENT OFFICE.

ROY W. WEIR AND WILLIAM LOWERY, OF HAMMOND, INDIANA, ASSIGNEES TO
MARVEL COMPANY, OF HAMMOND, INDIANA, A CORPORATION OF OHIO.

SUCTION SWEEPER.

Application filed July 14, 1919. Serial No. 310,606.

To all whom it may concern:

Be it known that we, Roy W. WEIR and WILLIAM LOWERY, citizens of the United States, residing at Hammond, in the county 5 of Lake and State of Indiana, have invented a certain new and useful Improvement in Suction Sweepers, of which the following is a specification.

Our invention relates to improvements in 10 suction sweepers and has for one object to provide a new and improved form of hand operated suction sweeper, particularly of the type wherein a fan is used to suck up dust laden air and discharge it into a bag.

15 Sweepers of this type have been used before wherein there was a train of gears between the supporting axle and the fan whereby a forward movement of the housing would cause a rotation of the supporting 20 wheels and thus drive the fan, the rear movement leaving the fan and gear train free to go forward because it was connected through an overrunning or ratchet clutch.

25 Experience has, however, shown that an apparatus of this type, wherein the overrunning clutch was between the gear train and the axle, as has been the past practice, was not satisfactory because it made it necessary for the fan to carry the gear train with 30 it as it ran forward, dissipating a large proportion of the stored energy on the return stroke. The result was that, owing to the friction of the gear train, the fan decelerated too rapidly and the suction during the re-

35 turn stroke was very much too low. Owing to the delay while the fan speeded up on the forward stroke, it was too low there also. By our invention, we provide a free fan which stores energy on the forward stroke 40 and which is disconnected altogether from the balance of the mechanism on the return stroke and thus is able to apply all its stored energy to the work of drawing in the dust laden air.

45 Our invention is more or less diagrammatically illustrated in the accompanying drawings, wherein—

Figure 1 is a side elevation of our cleaner with parts removed;

50 Figure 2 is a bottom view of our cleaner with parts removed;

Figure 3 is a section on the line 3—3 of Figure 2;

Figure 4 is a section on the line 4—4 of 55 Figure 1.

Like parts are indicated by like characters throughout the several figures.

A is a forwardly extending suction casing with a suction nozzle A¹ which has a suction inlet A² with a brush A³ mounted therein in any suitable way. Leading to the fan casing in the rear is the vacuum passage A⁴. Adjacent the center of the brush is a pulley A⁵ adapted to be surrounded and rotated by a belt A⁶ which enters the bottom of the mouth through the slit A⁷. It is driven by the pulley B on the wheel B¹ which is rotated by contact with the surface to be cleaned which it engages by the two rims B² surrounding the pulley B and preferably surfaced with rubber or other frictional material. The wheel and pulley are mounted in a yoke B³ which is pivoted at its front on the underside of the nozzle casing. The opposite end of the yoke is engaged by a set screw B⁴ the rotation of which adjusts the height of the wheel and thus of the suction nozzle. The suction top of the rearward extension of the suction casing forms a relatively flat platform C, of substantially circular contour, on which is mounted the fan casing C¹ which is preferably cast separate and secured to the rest of the casing by any suitable means. A horizontal fan C² is mounted therein on a vertical shaft C³. The passage A⁴ leading from the suction nozzle lies in advance of the axis of the fan, and terminates in a substantially horse-shoe shaped opening in the platform C which communicates with the bottom of the fan chamber. This opening extends around the fan shaft and is directly beneath the fan. The fan shaft penetrates the platform C and projects down into the gear housing D beneath it being journaled as at D¹. The housing D depends from the rear portion of the platform C and the suction casing A and has a removable bottom D². Intermediate its ends within this housing the fan shaft carries a pinion sleeve D³ in engagement with the horizontal gear E on the stub shaft E¹ journaled in and depending from the platform C. The gear E lies between the shaft F¹ and the platform C. Beneath the gear E the stub shaft carries on its end a beveled pinion E² which engages a vertical bevel gear F on the shaft F¹ which latter passes through the gear housing and is rotatably supported in lugs F³ depending from the platform C. 100 105 110

This shaft carries the wheels F^4 F^4 on which the suction casing is supported, these wheels being preferably surrounded by frictional rims F^5 of rubber or other suitable material. Within the gear F is a roller ratchet comprising the indentations F^6 on the inside of the gear, the rollers F^7 therein, and the springs F^8 adapted to keep the rollers seated against the bearing surface F^9 on the shaft 5 F^1 . When the machine is pushed forward, by the inclination of the ratchet the rollers engage the bearing surface on the shaft and the ratchet bearing surface on the inside of the gear and the gear rotates with the shaft, 10 taking its rotation from the friction of the wheels F^4 on the floor. When the machine is drawn backwards, the rollers are pushed out against the springs, but the springs keep them in constant contact with the bearing 15 surface, so that the clamping action, when the direction is reversed, is almost instantaneous. The upper end of the fan shaft C^3 has milled in it the elongated flute members G and within them are located the 20 ratchet rollers G^2 . The depending elongated fan hub G^3 surrounds and engages the ratchet rollers, but is out of contact with the ratchet member, and is supported loosely 25 on a single ball bearing G^4 mounted in the socket at the top of the ratchet member. The lower end of the shaft C^3 fits within 30 and projects below a horizontal perforated guide lug C^4 formed on the suction casing A within the housing D , and at its projecting extremity said lower end of the shaft C^3 is provided with a ball bearing G^5 . This bearing and the guide lug C^4 insure true 35 running of the shaft C^3 and proper balancing of the loosely mounted fan C^2 at the upper end of said shaft. It will be understood, of course, that this disposition of ball 40 bearings might be varied; the essential point is that the fan rotates freely, and carries with it only its own hub. When the machine is pressed forward, the clutch within this hub drives the fan. The instant forward acceleration ceases, the ratchet clutch automatically breaks its connection 45 and the fan rotates freely on the ball bearings, utilizing all of its force and momentum 50 in maintaining its own speed and suction. Mounted on the depending lugs F^3 are projecting studs or screws H on which the prongs H^1 of the handle bail are rotatably 55 mounted. The studs H are so positioned that when the handle bail is horizontally positioned, it rests on the shaft F^1 . When the handle bail is in upright position or rather is tilted slightly forward, it is supported by projections H^2 H^2 on the suction 60 casing. A handle H^4 of any suitable type is mounted in the handle bail and supports the outer end of the bag H^6 , the inner end of which is clamped about the outlet H^7 in 65 the fan casing.

It will be understood that while we represent an operative device, the parts and arrangement of parts may be varied in many ways without departing from the spirit of our invention and we wish, therefore, that our drawings be regarded as in a sense diagrammatic.

The use and operation of our invention is as follows:

The housing or truck is supported on 75 wheels as shown. These wheels are preferably rubber tired to that there will be a strong frictional connection between them and the floor or floor covering. The nozzle carried by the housing or frame work extends down close to the floor covering, and there is a suction passage leading from it to the fan chamber. There is a gear train enclosed within a dust tight housing and leading from the axle to the fan and driving it. The fan discharges the dust laden air through a passage into a dust bag supported partially on the housing and partially on the operating handle, whereby the dust is separated out of the air and the material picked up from the carpet is retained. 80 while the air passes on.

The overrunning clutch is located within the fan hub which latter fits over and embraces the ratcheted upper end of the fan 85 shaft C^3 . The fan C^2 thus is loosely mounted on the upper end of the shaft C^3 and wholly supported by the latter, the closed upper end of the fan hub resting on the single ball bearing G^4 . By reason of the 90 elongated ratcheted upper end of the shaft C^3 and the elongated hub G^3 of the fan an extended bearing for the latter is provided, thereby insuring steady balanced movement to the fan in its rotation. By the construction described the fan is also permitted to rotate freely and without having to carry the gear train with it. Thus it keeps its speed 100 and does effective cleaning on the return stroke as well as on the forward stroke, and 105 experience shows that it maintains, at all times, a speed sufficiently high to do effective cleaning. Since the friction gear itself is not driven on the back stroke, wear and tear is reduced, and the weight of the 110 stroke required is lessened.

We claim:

1. In a suction sweeper of the class described, the combination with a suction casing including a forwardly extending suction nozzle, a rearward extension the top of which is flat to provide a platform, and a gear housing depending from said platform and arranged at the rear of said casing, of a vertical fan shaft fitted in said platform, the lower end of said fan shaft being journalled in said housing and the upper end of which is free, a horizontal fan loosely mounted on the free end of said shaft and wholly supported by the shaft above said 120 125 130

platform, the latter having an opening beneath said fan in communication with said suction casing, a fan casing associated with said platform and enclosing said fan, a 5 clutch between said shaft and said fan to drive the fan in one direction of movement of said shaft, a wheel-supported driving shaft extending through said gear housing, and gear connections within said housing 10 between said driving shaft and said fan shaft.

2. In a suction sweeper of the class described, the combination with a suction casing including a forwardly extending suction nozzle, a rearward extension the top of which is flat to provide a platform, and a gear housing depending from said platform and arranged at the rear of said casing, of a vertical fan shaft fitted in said 15 platform, the lower end of said fan shaft being journaled in said housing and the upper end of which is free, a horizontal fan loosely mounted on the free end of said shaft and wholly supported by the shaft 20 above said platform, the latter having an opening beneath said fan in communication with said suction casing, a fan casing associated with said platform and enclosing said fan, the upper end of said fan shaft having 25 an elongated bearing surface, the fan having an elongated depending hub fitting over the bearing surface of said shaft, said bearing surface and said depending hub providing an extended bearing for the fan to insure balanced movement of the fan in its 30 rotation, a clutch between said shaft and said fan to drive the fan in one direction of movement of said shaft, a wheel-supported driving shaft extending through said gear 35 housing, and gear connections within said housing between said driving shaft and said fan shaft.

3. In a suction sweeper of the class described, the combination with a suction casing including a forwardly extending suction nozzle, a rearward extension the top of which is flat to provide a platform, and a gear housing depending from said platform and arranged at the rear of said casing, of 45 a vertical fan shaft fitted in said platform, the lower end of said fan shaft being journaled in said housing and the upper end of which is free, a horizontal fan loosely mounted on the free end of said shaft and wholly supported by the shaft above said platform, the latter having an opening beneath said fan in communication with said suction casing, a fan casing associated with said platform and enclosing said fan, the upper end of said fan shaft having an elongated ratcheted clutch to drive the fan in one direction of movement of said shaft, the fan having an elongated depending hub fitting over the ratcheted clutch of said fan shaft, said ratcheted clutch and said depending hub 50 providing an extended bearing for the fan to insure balanced movement of the fan in its rotation, the upper end of the fan shaft also having a socket, a bearing ball seated in said socket and on which the closed end of the hub of the fan rests and is supported, a wheel-supported driving shaft extending through said gear housing, and gear connections within said housing between said driving shaft and said fan shaft. 55

Signed at Hammond, Indiana, this 10th day of July 1919.
